UNITED STATES PATENT OFFICE.

ADALBERT JOSEPHSON, OF NEW YORK, N. Y.

DISPLAY-CARD.

1,273,377.

Specification of Letters Patent. Patented July 23, 1918.

Application filed March 14, 1918. Serial No. 222,297.

To all whom it may concern:

Be it known that I, ADALBERT JOSEPHSON, a citizen of the United States of America, residing at New York city, in the county 5 and State of New York, have invented certain new and useful Improvements in Display-Cards, of which the following is a specification.

My invention relates to an improved display card, and is particularly adapted for use as a card which in a sense forms the false bottom of a container, and to which card objects to be displayed are attached.

The invention has especial reference to the 15 means by which such objects are releasably retained by the card. I am familiar with numerous devices at present in use, but so far as I am aware none of these has proven entirely satisfactory. In most cases the retaining member is either pasted or sewed 20 to the base card, and not only is the cost of production of such cards considerable but the life of the cards is relatively short and they are generally unsatisfactory in use.

The principal purpose of my invention is 25 to overcome the defects of existing display cards of this character and to provide a simply constructed card which may be cheaply produced and in which the retaining member proper may be replaced as often as 30 desired, and when in position will be firmly anchored to retain the objects in display position.

The invention may be embodied in a great 35 variety of forms, and for the purpose of illustrating a concrete form of my invention I have shown a display card in the accompanying drawing, in which—

Figure 1 is a top plan view with one of 40 the display objects omitted; and

Fig. 2 is a sectional view on the line 2—2 of Fig. 1 looking in the direction of the arrows.

The form of the card itself is immaterial, 45 and in the drawing the numeral 10 denotes a rectangular base card to which the objects 11 are to be releasably secured. The objects shown in the drawing are buoyant animals which may float on a toy pond.

It is desired that these animals shall be 50 fairly firmly secured to the base 10 so that the base with the superposed animals may be handled and shipped as a whole, and withal these animals must be easily removable from the base card and as easily replaceable thereon in proper position. To this

end I provide the base card with slots 12 so as to form suitably shaped tongues or lugs 13 constituting what may be termed "anchors" under which elastic retaining elements 14 60 are passed. The particular configuration of the tongues 13 is immaterial provided these tongues are so shaped that oppositely disposed tongues will securely retain one of the members 11 in position on the card. In 65 the drawing each tongue 13 is formed somewhat like a wing, comprising the intermediate portion A, and the side wings B which are rearwardly curved and merge in the line C by which the wing remains attached to 70 the web of the base card 10.

The elastic element 14 desirably consists of an integral endless rubber band. For each object 11 to be attached to the base card a pair of such lugs 13 is provided and a 75 single rubber band 14 is anchored under the side wings B of the lugs 13, while the main portion of the rubber band consisting of the oppositely disposed strands rests on top of the card 10. The band may be of such 80 length that the visible strands in Fig. 1 are under very slight tension in the position of rest. It will be obvious that to secure one of the objects 11 to the card 10 it is merely necessary to raise the strands of the band 14 85 and to slip the object 11 under the strands so that the latter are spaced apart and engage the body of the object 11 at different places. The elastic band 14 being anchored in what may be termed the corners or edges 90 between the side wings B is held firmly in position and will not be pulled out nor will it tend to pull out the lugs 13 when one of the objects 11 is placed under the band 14.

The manner of using the device has been 95 sufficiently indicated in the foregoing description so that the operation of the device is clear.

What I claim is:—

1. A display device of the character specified, comprising a base card having slotted portions therein, arranged in pairs, the members of each pair being opposite each other, and a separate single elastic band engaging each pair of such slotted portions 100 and extending between the members thereof to receive objects to be displayed on said card.

2. A display device of the character specified, comprising a base card having slots 110 cut therein to form oppositely disposed pairs of wings and a separate single elastic

member for each pair of wings having portions within the slots and under the wings, and additional portions extending over the face of the card substantially at right angles to the slots in position to receive objects and releasably retain the same on the card.

3. A display device comprising a card having lugs cut from the web of such card, said lugs being arranged in pairs, the members of each pair being opposite each other, each lug comprising an intermediate portion and rearwardly curved side portions,

and a separate single elastic band for each pair of lugs having opposite sections thereof retained by the side portion of the lug 15 and strands of the band extending across the face of the card in position to releasably retain the objects on the card.

In testimony whereof I have affixed my signature in presence of two witnesses.

ADALBERT JOSEPHSON.
